CORPORATION OF NEW YORK

IGNITION COIL AND CONTROLLING DEVICE THEREFOR

Application filed May 6, 1932. Serial No. 609,666.

This invention relates to improvements in ignition coils for internal combustion engines; and especially to the generating coil of a magneto for ignition apparatus and the circuit controlling devices therefor.

An object of the invention is to provide an ignition coil of the high tension type adapted to be energized by a magnetic flux, and having the terminals of its high tension winding connected directly to the spark plugs of the internal combustion engine without the interposition of a distributor of the usual type.

The invention is particularly useful for two-cylinder two-cycle engines which require a spark at every half revolution; and it enables the magneto to dispense with the usual carbon holder or distributor for selecting the cylinder in which the spark is to be produced.

A further object of the invention is to provide a simple ignition coil which has high and low tension windings and which can be easily mounted and effectively operated in connection with a magneto that can be incorporated into the flywheel of an internal combustion engine, with magnets that are rotated by the flywheel and carried thereby into position to energize the coil. In practice the necessary circuit controlling devices for the coil are also actuated by the flywheel shaft.

The foregoing and other objects and advantages of this invention are set forth in the ensuing specification and the novel features pointed out in the appended claims; but, of course, the right is reserved to make such changes in the shape, size and arrangement of the parts as fall within the principle of the invention.

On the drawing:

Fig. 1 is a somewhat diagrammatic view showing an embodiment of the invention in front elevation; and

Fig. 2 is an end view seen from the right of Fig. 1.

The same numerals identify the same parts throughout.

The body of the coil is shown at 1 and it may if desired be enclosed in a suitable cover

or casing which will house the primary turns 2 and the secondary turns 3. One end of the primary windings will be grounded at 4 and the opposite end will be connected to a movable interrupter lever 5 carrying a contact 6 which engages a fixed contact 7, also connected to ground. This coil may be mounted upon a suitable support adjacent the flywheel or other moving part of an internal combustion engine and said part will carry the magnets, not shown, for directing a magnetic flux through said coil periodically and withdrawing said flux, to energize this coil. Both the coil and the magnets may have polepieces of any suitable shape. For a two-cylinder two-cycle engine the coil will be energized twice in each revolution, and the magnets on the moving part of the engine may be bar magnets and may have their polepieces carried into position at every half revolution to cooperate with the coil.

The terminals of the secondary or high tension winding 3 will be connected separately by leads 10 and 11 to the two spark plugs in said two-cylinder engine indicated at 12 and 13. The conductors 10 and 11 are continuous and permanently united to the terminals of the secondary, but the ignition current passes to only one spark plug at a time and produces a spark thereat because of a suitable circuit controller mounted on the shaft 14; which may be the shaft carrying the rotating magnets. This shaft also carries a cam 15 for actuating the circuit breaker lever 5.

Each of the terminals of the high tension coil is also connected to one of the fixed terminals 16 and 17, arranged 180 degrees apart; and these terminals are controlled by a member 18 on the shaft 14 having a cooperating projection 19. The member 18 is of conducting material and as it revolves each end of the secondary will be grounded in turn.

In operation, when the shaft 14 revolves, the magnets, not shown, will be carried into cooperative relation with the coil to energize the latter at each period of ignition; and at the proper instant one projection of the double cam 14 will actuate the lever 5, to separate

the contacts 6 and 7. A spring, not shown, may be connected to the lever 5 so that the contacts 6 and 7 are normally held in engagement. At the same time the projection 19 on 5 the member 18 will connect one end of the secondary 3 to ground by way of the terminal 16. Hence the circuit will be through the conductor 11 to the spark plug 13 and by way of ground to the other terminal of the coil. 10 10 A half revolution later a spark will be produced at the plug 12 because the opposite terminal of the secondary will be connected to ground by way of the terminal 17.

It will be seen from this arrangement that 15 both the primary and secondary circuit are properly controlled and a spark will pass in each cylinder of a two-cylinder two-cycle engine in succession as required. This construction is very simple and involves relatively 20 little expense to produce because the usual distributor which involves considerable insulation and carefully attached leads to the spark plugs is not needed. When the sparking instant arrives for either of the spark 25 plugs indicated at 12 or 13 the conductor leading thereto will be the high tension terminal of the coil and the terminal 16 will be connected to the low tension terminal of the coil so that less efficient insulation for the terminals 16 and 17, which are successively 30 connected to ground, can be utilized.

Having described the invention, what is claimed is:

35 1. An ignition coil comprising a primary and a secondary winding, a circuit breaker comprising a fixed and movable contact and a cam having one or more projections to control the circuit of said primary winding, a fixed terminal connected to each end of the secondary, a permanent connection for a 40 spark plug to be united to each end of the sec-

ondary winding, and a substantially circular member of conductive material rotating with said cam and having a projection on its circumference to ground the terminals of the secondary by turns, said member and said terminals being so disposed that said projection, as said member rotates, passes in proximity to each of said terminals in succession but without making contact therewith, in conjunction with the action of said cam, whereby when the primary circuit is opened one of the ends of the secondary will be connected to ground and a spark will be produced at the plug connected to the other terminal of the secondary.

2. An ignition coil comprising a primary and a secondary winding, a circuit breaker for controlling the primary winding, conductors for permanently connecting the opposite terminals of the secondary to spark plugs in which ignition is to be produced at separate instants, a fixed terminal likewise connected to each end of the secondary, and means for grounding each of said fixed terminals of the secondary in succession so that when one end of the secondary is grounded the spark can be produced at the plug connected to the other end of the secondary, said means comprising a member of conductive material movable with respect to the same axis as the circuit breaker and extending radially from said axis and having a terminal portion, the said fixed terminals being disposed so that said terminal portion moves into proximity thereto but does not contact therewith periodically to short circuit the spark plug connected to each of said terminals in succession.

In testimony whereof I affix my signature.

WOLFGANG E. SCHWARZMANN.
